DESIGN FOR A SHOE

George Rosenfield, New York, N. Y.

Application July 30, 1934, Serial No. 52,737

Term of patent 3½ years

To all whom it may concern:

Be it known that I, GEORGE ROSENFIELD, a citizen of the United States, residing in New York, in the county of New York, and State of New York, have invented a new, original, and ornamental Design for a Shoe, of which the following is a specification, reference being had to the accompanying drawing, forming part thereof.

I claim:

The ornamental design for a shoe, as shown.

GEORGE ROSENFIELD.
